UNITED STATES PATENT OFFICE.

JOHN F. BRADY, OF CHICAGO, ILLINOIS.

MEANS FOR CONSERVING LIQUID GASES.

SPECIFICATION forming part of Letters Patent No. 662,217, dated November 20, 1900.

Application filed March 29, 1899. Serial No. 710,998. (No model.)

To all whom it may concern:

Be it known that I, JOHN F. BRADY, a citizen of the United States, residing at Chicago, in the county of Cook and State of Illinois, 5 have invented a new and useful Means for Conserving Liquid Gases, of which the following is a specification.

My invention relates to means for conserving liquid gases; and my object is to provide 10 a construction adapted to hold the gas in a liquid state for a great length of time, so that it may be shipped to a great distance or be held in stock for any use for which it may be adapted without the enormous loss incident 15 to the employment of conserving vessels of the ordinary class, the same being described hereinafter and illustrated in the accompanying drawings, in which—

Figure 1 is a vertical axial section on broken 20 line 10, Fig. 3, showing the general construction and relation of the principal parts, and also illustrates the course of the current of expanding waste gas for refrigerating the outer and inner gas-chambers. Fig. 2 is a 25 cross-section on broken line 5 6 of Fig. 1 to illustrate the arrangement of double gas-chambers from which the waste gas is directed around in the spaces between the several nested spheres, which in this instance 30 comprise the main body of the apparatus. Fig. 3 is a horizontal nearly axial section on broken line 7, Fig. 1, of the main body portion of the apparatus to illustrate the disposition of several vertical partitions between 35 the walls of the nested spheres. Fig. 4 shows, respectively, a plan and a cross-section on broken line 8 9 of one of the heat-insulating bearing-rings which are disposed below three of the internal spheres, and not only hold 40 them apart, but serve to bear their weight and assist in preserving their concentric position.

Similar letters indicate like parts throughout the several views.

45 In this instance there are four spheres, of which three, A, B, and C, are nested within the outer sphere D, the spheres being separated by means of the base-rings E, F, and G and top rings E', F', and G', so that spaces 50 E², F², and G² are formed between them. Each of the spheres in this instance is covered with a good heat non-conductor, such as wool-

felt or the like, as indicated at A', B', C', and D'. The central chamber A contains the liquid gas, as indicated in Fig. 1. At the top portion of the spheres are circular heads H, I, J, and K, adapted to screw into rings firmly secured to the margins of holes in the spheres, and each head is provided with an outwardly-opening spring-controlled valve, such as H', 55 I', J', and K'. The top insulating-rings E', F', and G', the heads H, I, J, and K, and the vertical partitions L, M, and N form six semi-circular chambers L' L², M' M², and N' N². There are passage-ways O P Q and O' P' Q' 60 from these chambers which lead into spaces E², F², and G² between the spheres. There are also passage-ways through the base-rings E, F, and G at R S T and R' S' T' for connecting the spaces E², F², and G² outside of 65 the rings with the portions of such spaces enclosed by the rings. There are vertically-disposed partitions E³, F³, and G³, E⁴, F⁴, and G⁴, and E⁵, F⁵, and G⁵, whose upper ends join the top rings E', F', and G' and the lower 70 ends join the base-rings E, F, and G.

The base and top rings E, F, and G and E', F', and G' should be made of some soft wood, or of a compressed fibrous material—such as wool, asbestos, or a combination of materials—80 to insure sufficient stability to hold the several spheres in proper position without undue shifting when being transported, and at the same time form as nearly as possible a perfect insulator against the passage of heat inwardly to the liquid-gas chamber in sphere A. The vertical partitions should also be made of a material having similar qualities described for the rings. Copper covered with an insulating coat of some good non-conductor 85 of heat, like wool-felt, is preferable for the two centrally-located spheres, but more especially for the liquid-gas sphere A. If the temperature is prevented from falling so low in the outer spaces F² and G² as not to injure the strength of steel, this metal, covered with a good non-conductor, would be suitable 90 for the construction of spheres C and D.

A liquid gas introduced into central sphere A would forever remain in the liquid state if 100 heat could be prevented from penetrating the walls of the several nested spheres, and since no material exists which is a perfect insulator of heat the latter will slowly penetrate each

successive insulated sphere-wall and finally raise the temperature of the external surface of the liquid gas above the critical point, when it will expand, and when under sufficient pressure lift valve K' and pass out into chamber N², and thence out through passage-way Q' into space E² and downward and through passage-way R' in ring E, thence around the bottom of the liquid-air chamber A and through passage-way R in ring E, thence upwardly in space E² and through passage-way Q into chamber N'. Thence when sufficient pressure has been attained valve J' is raised and the gas passes up into chamber M', thence through passage-way P, space F², and passage-ways S and S', through base-ring F, and passage-way P' through top ring F' into chamber M². Then by sufficient pressure it lifts valve I' and passes into chamber L², thence out through passage-way O', space G², passage-ways T' and T in base-ring G and up space G² and through passage-way O in top ring G' into chamber L', when the gas under a sufficient pressure will lift valve H' and pass out into the atmosphere or into a means for conveying it to a place where it may be additionally utilized.

It is obvious that the waste gas from the liquid in sphere A may be made to prevent all but a very small per cent. of heat from reaching the liquid-gas chamber.

It will be understood that the top portion of this apparatus around and upon head H will be covered with a good non-conductor of heat, such as a cap made of some material like wool or hair felt, but it is not shown in the drawings.

It is obvious that the rings hereinbefore described for holding the spheres concentric and the arrangement of the vertical partitions for compelling the current of cold gas to pass around the spheres may be arranged in many other ways than as shown without changing the general intent of these parts. It will also be understood that the several spheres may be substituted by vessels of several other shapes, for it is obvious that when apparatus of this kind is made of large size a cylindrical shape would cost much less and serve the same purpose.

I claim as my invention—

1. In a means for conserving liquid gas, a series of heat-insulated receptacles, one within the other, communicating heads between the vessels, each of which is provided with laterally-opening passages, valves and a partition in each head, and partitions within the spaces between the receptacles extending

from opposite sides of the heads between the passages.

2. In a means for conserving liquid gas, a central receptacle adapted to contain liquid gas, a series of casings nested around the central receptacle, and each casing insulated from the other and from the central receptacle, by means of a slow heat-conducting material, which latter also serves to separate the several casings from each other and from the central receptacle, and form spaces for containing gas around between the several casings and between the central receptacle and the innermost casing, in combination with valves operated by gas-pressure which guard a passage-way leading out of the central receptacle, and passage-ways leading out of the casings into the said spaces and out of the outer casing, in combination with means without the spaces adapted to direct gas from the central receptacle around itself, and around the casings for the purpose stated.

3. In a means for conserving liquid gases, a series of heat-insulated receptacles, one within the other, each provided with an outwardly-opening valve and the central one being adapted to contain liquid gas, and means between the receptacles for causing the gas to circulate in reverse directions in the spaces between the receptacles in its passage from the interior to the exterior of said receptacles.

4. In a means for conserving liquid gases, a series of heat-insulated vessels, one within the other, each provided with a head, and each head being provided with spaces, each space communicating with the adjacent space between the vessels, and one of the spaces in each alternate head communicating with the corresponding space of the next succeeding head, and an outwardly-opening valve in each of the passages between the heads.

5. In a means for conserving liquid gases, a series of nested heat-insulated vessels, each provided with a head, each head being provided with spaces, said spaces communicating with the adjacent space between the vessels, and one of the spaces of each alternate head communicating with the corresponding space of the next succeeding head, an outwardly-opening spring-pressed valve in the passage from one head to the other one, and top and base rings within the spaces between the different vessels, said rings being provided with gas-passages.

JOHN F. BRADY.
